UNITED STATES PATENT OFFICE.

WILLIAM E. PEARSON, OF BOSTON, MASSACHUSETTS.

BRAKE AND POWER APPARATUS FOR ELECTRICALLY-DRIVEN VEHICLES.

SPECIFICATION forming part of Letters Patent No. 634,832, dated October 10, 1899.

Application filed March 4, 1899. Serial No. 707,779. (No model.)

To all whom it may concern:

Be it known that I, WILLIAM E. PEARSON, of Boston, in the county of Suffolk and State of Massachusetts, have invented a new and useful Improvement in Brake and Power Apparatus for Electrically-Driven Vehicles, of which the following, taken in connection with the accompanying drawings, is a specification.

10 My invention relates to an apparatus for operating the brake mechanism and the power-controlling device for electrically-propelled vehicles; and it consists in the construction and arrangement of parts in such a manner that the user by operating a single hand-wheel or its equivalent can promptly govern both the brake and power mechanism of any vehicle of this class.

15 A form of mechanism in which my invention is embodied is illustrated in the accompanying drawings, in which—

20 Figure 1 is a view showing in front-elevation one form of my invention as applied to a car, the mechanism being shown as suspended crosswise under the platform at the end of the car. Fig. 2 is a plan of the mechanism as it would appear were the platform removed. Fig. 3 is a plan showing some of the parts shown in Fig. 2, but in different positions. Fig. 4 shows, partly in elevation and partly in section, parts that are shown in plan in Fig. 3. Fig. 5 is a cross vertical section taken on line $x-x$ of Fig. 3; Fig. 6, details, partly in section and partly in elevation. Fig. 7 is a view from the under side of one of the parts; Figs. 8, 9, 10, and 11, details.

25 The platform of an electric car is represented by A in Fig. 1. Suspended under this platform and crosswise of the car is the mechanism of my invention. (Shown entire in Figs. 1 and 2 and in detail in the other figures.) A base-plate E has ears E' E' E' E', by which and the hangers A' A' it is held to the platform A of the car. This base-plate 30 E is made trough-like in cross-section, as shown in Fig. 5, and supports a slide C'. The slide C' has a rack C² on its side, which meshes with the pinion-gear C on the brake-shaft B, and also a rack C³, which meshes with a pinion D on the shaft D' of the electric controller D² of the car. A spring C⁴, held in place by the yoke-piece C⁵, rests upon the slide C' and

assists in holding it in place. A pin C⁶ is connected to the slide C', the use of which will be explained.

35 The brake-shaft B has a second pinion B⁶, which meshes with a rack on the sliding plate K. The plate K is held by the way-piece E², which is made fast to the base-plate E. The plate K has a long narrow opening k' k², Fig. 2, in which a pin C⁷ operates.

40 The brake-chain B⁵ is connected to an arm B⁴ on a sleeve B³, attached to the brake-shaft B. A pin B² on the brake-shaft B limits the free movement of the sleeve B³—that is, while 45 the shaft B may turn nearly a whole rotation without moving the sleeve B³, yet as soon as the pin B² comes in contact with the arm B⁴ on the said sleeve then the sleeve must turn with the brake-shaft, and thus wind 50 up or loosen the brake-chain, as the case may be.

45 A device for giving motion to the slide C' after the pinion C has carried it to the limit of the rack C² consists of a swinging collar 55 L, loosely mounted on the brake-shaft B, resting upon the upper side of the pinion C and held from slipping upward by the collar L', which is rigidly held in place by the set-screw L². The swinging collar L has an arm 60 L³, which acts at certain times on the pin C⁶ on the slide C', as will be hereinafter set forth.

50 The swinging motion of the collar L is limited in one direction by a pin L⁴ on the pinion C and controlled by a spring S, (see Fig. 7, a 65 plan in reverse,) one end of this spring resting upon stop S', made in the groove S³, and the other end abutting against a stud S², projecting from the face of the pinion C. This arrangement will admit of the collar L and 70 its arm L³ to rotate or swing (compressing the spring S) to a limited extent in the direction of the arrow W.

55 For convenience in throwing on the electric current without operating the brake-wheel and its connected mechanism, as may be required when the vehicle is on an upgrade, the following-described well-known device is used: A rod F, bent as shown at F', Fig. 2, so as to engage with the end of the slide C', is connected at F⁶ with the lower end of the bent lever F⁷, (pivoted at F⁸.) This lever F⁷ is operated by foot-bolt F⁹. The spring F⁵ serves to throw the rod F forward 60

when not drawn back by the action of the foot-bolt and bent lever.

The operation of the parts may be explained as follows: The operator in handling the wheel B' is enabled to let off the brake and turn on the electric current, or he may cut out the current and turn on the brake—that is, he, under ordinary circumstances, controls the vehicle by the use of the hand-wheel B' alone. To start the vehicle, he turns the hand-wheel backward—that is, against the arrow W —the position of the parts being as indicated in Figs. 3 and 4. This lets off the brake-chain B^5 and, acting through the pinion B^6 and rack on plate K , throws the plate K in the direction of the arrow V . This motion of the plate K causes the pin C^7 , which is now at the extreme right-hand end of the narrow opening $k' k^2$ in the said plate, to move to the left and draw the slide C' with it. This action will continue until the slide C' has been drawn so far to the left that the teeth on the pinion C will engage with the rack C^2 on the said slide C' . Now the slide C' will be forced to the left at a greater speed than before, and as both the pinions C and B^6 are in mesh with their racks the plate K will not move so fast as the slide C' , thus causing the pin C^7 to advance in the narrow opening $k' k^2$ toward the end k' . To provide for the movement of the arm L^8 on the collar L , which will come in contact with the pin C^6 on the slide C' and have a tendency to move faster than the said pin, the spring S is used. This spring allows the said arm to lag until it has passed so far to the left in its rotation that it will slip off the pin and then be thrown back to its resting position against the pin L^4 on the pinion C . While these motions have been going on, the rack C^3 , Fig. 2, has been rotating the pinion D on the shaft D' of the electric controller D^2 and the current has been turned on, causing the vehicle to advance.

To stop the vehicle—that is, to put on the brake and turn off the current—the operation is as follows: The hand-wheel B' is turned in the direction of the arrow W . This movement of the hand-wheel will not at first act on the chain of the brake, as the pin B^2 will be on the wrong side of the arm B^4 , (see Figs. 4 and 5,) it requiring nearly a full turn of the brake-shaft to bring the pin B^2 into contact with the arm B^4 . This pin is shown in working contact with the arm in Fig. 1. As soon as the pin B^2 strikes the arm B^4 , the brake-chain begins to be wound up and the brake is applied. In the meantime the pinion C is operating the rack C^2 of the slide C' , and through this slide and its rack C^3 the pinion D is rotated. The rotation of the pinion D gives motion to the shaft D' of the electric controller in D^2 , and thus cuts off the current. Thus the brake is applied and the current is cut off by the action of the hand-wheel alone. When the pinion C has carried the slide C' so far to the right that the

teeth C^2 of the rack have passed beyond the action of the teeth of the pinion C , then the arm L^8 will engage with the pin C^6 on said slide C' and force it still farther to the right, so that in reversing the direction of the hand-wheel it will not at first affect the slide C' , but will act through the pinion B^6 and cause the plate K to move back in the direction of the arrow V and, acting on the pin C^7 , draw the slide C' back, so as to cause its rack C^2 to engage with the pinion C , as has been already explained. To prevent the slide C' from being thrown so far back (by the action of the foot-bolt F^9) as to engage with the teeth of the gear-wheel C , I have the following-described device, (see Fig. 8:) A flat spring R^2 has attached to it a stop-pin R , which is normally in the path of the slide C' , so as to stop it when desired, and thus allow the operator to turn the hand-wheel B' without affecting the electric-current device. When it is desired to operate the current device, the turning of the hand-wheel to the left will cause the slide K to move to the left. This motion of the slide will cause the projection K' on said slide to come in contact with a cam-piece R^3 on the spring R^2 and force it outward, thus removing the pin R from the path of the slide C' , so that it can be drawn into engagement with the gear C , as has been described.

In Figs. 9, 10, and 11 I have shown a modification of the device shown in Fig. 7 for giving motion to the slide C' after the pinion C has carried it to the limit of the rack C^2 . This device consists of a latch M , pivoted at M^2 and having side guards $M' M'$ and a check-pin M^3 . This latch M takes the place of the arm L^8 in Figs. 3 and 7, the incline C^8 taking the place of the pin C^7 , the action of the two devices being practically the same. Thus when the wheel C , Fig. 10, is going in the direction against the arrow then the latch M will slide up the incline C^8 without giving any motion to the slide C' ; but when the wheel C rotates in the direction of the arrow the latch M will come in contact with the left end of the incline C^8 and force the slide C' forward.

I claim—

1. In an apparatus of this class, a brake-shaft having a pinion-gear, a slide adapted to be operated by said pinion-gear, a rack upon said slide adapted to engage with and operate the electric-controller mechanism; a pin as C^7 on said slide engaging with a narrow opening in a sliding plate as K , the said sliding plate having a rack adapted to engage with a pinion on the brake-shaft and to be operated by it, whereby the motion of the sliding plate is at intervals communicated to the said slide; substantially as and for the purpose set forth.

2. In an apparatus of this class, a brake and shaft having a pinion-gear adapted to engage with the teeth of a rack on a slide, the said slide and a mechanism by which its motion is communicated to an electric controller; a pin (as C^6) on said slide adapted to engage with and be operated by a swinging arm (as

L³) on the said brake-shaft, the said swinging arm having limited rotative motion in relation to the brake-shaft, said motion being limited in one direction by a stop-pin (as L⁴) on said pinion-gear, and yieldingly controlled by a spring; substantially as and for the purpose set forth.

3. In an apparatus of this class, a brake and shaft having a pinion-gear adapted to engage with the teeth of a rack on a slide, the said slide and a mechanism by which its motion is communicated to an electric controller; a sliding plate as K having a projection K'

adapted to engage with a cam-piece, said cam-piece having a stop-pin, as R', adapted to engage with and check the motion of the controller-operating slide, substantially as and for the purpose set forth.

In testimony whereof I have signed my name to this specification, in the presence of two subscribing witnesses, on this 2d day of September, A. D. 1898.

WILLIAM E. PEARSON.
